UNITED STATES PATENT OFFICE.

NILS J. A. WAHLBERG, OF PITTSBURGH, PENNSYLVANIA, ASSIGNOR TO WESTINGHOUSE ELECTRIC & MANUFACTURING COMPANY, A CORPORATION OF PENNSYLVANIA.

TROLLEY DEVICE.

1,379,705.

Specification of Letters Patent. Patented May 31, 1921.

Application filed February 25, 1919. Serial No. 279,039.

To all whom it may concern:

Be it known that I, NILS J. A. WAHLBERG, a citizen of the United States, and a resident of Pittsburgh, in the county of 5 Allegheny and State of Pennsylvania, have invented a new and useful Improvement in Trolley Devices, of which the following is a specification.

My invention relates to devices for trolley 10 conductors and particularly to approaches for frogs, crossings and similar conductor attachments.

One object of my invention is to provide 15 a device of the above indicated character that shall be simple and durable in construction and inexpensive to manufacture.

Another object of my invention is to provide 20 an approach for a trolley-conductor device that, with its coöperating members, shall comprise a relatively small number 25 of parts and be readily mounted in operative position on a conductor by the use of a simple tool, such as a hammer.

In practising my invention, I provide a 30 removable extension member, for a frog or other trolley-conductor device, to take up the shocks and wear incident to the passage of trolley contact members and a holding member rigidly secured thereto that may be 35 readily moved to and from its holding position to permit mounting of the conductor. The holding member is provided with a slot through which a headed projection on a wedge member may be inserted and by a 90° turn, with respect thereto, be placed in operative position and prevented from withdrawal through the slot.

Figure 1 of the accompanying drawing, is a top plan view of a portion of a trolley frog 40 embodying my invention; Fig. 2 is a side view, partially in elevation and partially in section, of the device shown in Fig. 1, and Fig. 3 is a view, taken along the line III—III of Fig. 2.

45 A frog 1, for the reception of a trolley conductor 2, only one approach end 3 of which is shown, comprises a channel or body portion 4, of substantially U-section, in which the conductor is disposed and to 50 which the latter may be attached in any suitable manner. An extension member 5, preferably of malleable material, projecting from the end 3, has an inverted channel por-

tion 6 for embracing the conductor 2, a plain end face 7 that engages the end 3 and 55 a centrally projecting portion 8 disposed in the channel 4 above the conductor 2. Oppositely and outwardly projecting lugs or flanges 9 on the upper edge of the channel portion 4 at the end 3 support a relatively 60 flat holding member 10 that spans the channel of the body member of the frog 1 and is provided with a longitudinal slot 11 parallel to the channel. End portions 12 of the member 10 closely embrace the flanges 65 9 and are rigidly secured with respect thereto by being pressed or clamped thereon. A relatively flat wedge member 13 is provided, on one face, with a projection 14 of 70 rectangular cross section and having a head 15, the lateral thickness of which is greater than the width of the slot 11.

When assembling the device, the member 13 is turned at an angle of 90°, from the position shown in the drawings, with respect to the member 10, and the projection 14 is passed through the slot 11 in the member 10, after which the member 13 is again turned 90° to its operative position, shown in the drawings, where it is held against 80 disengagement from the member 10 by the head 15. After this operation, the member 10 is attached to the frog 1, as described above.

During the operation of attaching the 85 member 5 to the frog 1, the portion 8 is inserted in the end of the channel 4, between the conductor 2 and the wedge member 13, after which, the latter is driven toward the frog 1 to rigidly clamp the portion 8 90 against the conductor 2.

The arrangement permits the members 1, 10 and 13 to be transported as a unit, thereby reducing the number of loose parts and greatly facilitating the renewal of the 95 member 5.

While I have shown and described a particular form of my invention, changes may be effected therein without departing from the spirit and scope thereof, as set forth in the 100 appended claims.

I claim as my invention:

1. A trolley-conductor device comprising a body member of channel shape for the reception of the conductor and having outwardly-projecting flanges at its edges, a 105

- transverse member rigidly secured in a position spanning one end of the channel member and having its ends extending around said flanges, said transverse member having
- 5 a slot parallel to the channel, a wedge member disposed in the channel and having a headed projection adapted for insertion through said slot and then to be turned through an angle of substantially ninety degrees to lock it against withdrawal, and an
- 10 approach member having a portion disposed in the channel between said wedge member and the conductor.
2. A trolley-conductor device comprising
- 15 a flanged body member for the reception of the conductor, a slotted member rigidly secured across the end of said body member and embracing said flanges, a wedge member disposed between said body member and
- 20 said slotted member and having a headed projection extending through a slot in said slotted member for interlocking engagement therewith, and an approach member for engagement with said body member and having
- 25 a portion between said wedge member and the conductor.

3. A trolley-conductor device comprising a body member for the reception of the conductor, a member disposed adjacent to the
- 30 end of said body member and having a slot, a wedge member disposed between said members and having a portion formed to have releasable interlocking relation to the slotted member in said slot, and an approach
- 35 member held in position by said wedge member and the conductor.

4. A trolley-conductor device comprising a body member for engagement with the conductor, a holding member engaging said
- 40 body member, a wedge member disposed between said members, means for interlocking said holding member and said wedge member together, and an approach member hav-

ing a portion disposed between said wedge member and the conductor.

45

5. A trolley-conductor device comprising a body member for engagement with the conductor, a holding member releasably secured to said body member, a longitudinally-slidable wedge member engaging said holding member and an approach member held in position by said wedge member.

50

6. A trolley-conductor device comprising a body member having an end portion of substantially channel shape for the reception of a conductor, a wedge-holding member disposed over said end portion and a longitudinally slidable wedge adapted to be driven between the wedge-holding member and the conductor to clamp the latter in position.

55

7. A trolley-conductor device comprising a body member having an end portion of substantially channel shape for the reception of a conductor, a wedge-holding member disposed over said end portion and having a sloping wedge-engaging surface, and a wedge adapted to be driven between the wedge-holding member and the conductor to clamp the latter in position.

60

8. A trolley-conductor device comprising a body structure having an end portion of substantially channel shape for the reception of a conductor, a wedge-holding member disposed over said end portion, a renewable approach member having a portion disposed in said end portion, one of said members having a sloping wedge-engaging surface, and a wedge adapted to be driven between the wedge-holding member and the approach member to clamp the latter and the conductor in position.

65

In testimony whereof, I have hereunto subscribed my name this 19th day of Feb., 1919.

NILS J. A. WAHLBERG.
